UNITED STATES PATENT OFFICE.

WILLIAM SANGSTER, OF COVINGTON, VIRGINIA, ASSIGNOR TO COVINGTON MACHINE COMPANY, A CORPORATION OF VIRGINIA.

COAL-LEVELING MACHINE FOR BEEHIVE-OVENs.

1,089,675.

Specification of Letters Patent. Patented Mar. 10, 1914.

Application filed July 7, 1908. Serial No. 442,306.

To all whom it may concern:

Be it known that I, WILLIAM SANGSTER, a citizen of the United States, and resident of Covington, Alleghany county, State of Virginia, have invented a new and useful Improvement in Coal-Leveling Machines for Beehive-Ovens, of which the following is a specification.

My invention relates to improvements in machinery for leveling the coke within coke ovens, and particularly to that class of machine for leveling the coke in what are known as "beehive" ovens, as distinguished from other classes of ovens. The so called "beehive" oven is an oven made in the form of a hemisphere, access being had to the interior thereof, through a central opening in the top termed the "eye" and through an opening at the side on the level of the bottom through which the oven is discharged.

The present invention consists of a leveling device which is carried upon a carriage moving upon a track placed above and preferably at one side of a row of such beehive ovens, and which carriage by means of suitable power, is caused to travel along and over the row of ovens and by appropriate mechanism to insert the tool into each oven and then so rotate it preferably horizontally, that all parts of the coke within the oven will be successfully subjected to its effect, and then to withdraw it, move forward and then subject the next oven in the row to a similar procedure.

The invention will be best understood by reference to the accompanying four sheets of drawings in which—

Figure 1 is a vertical elevation of the leveling tool attached to the table of the carriage upon which it moves, shown in connection with a beehive oven in a vertical cross-section. Fig. 2 is a vertical elevation partly in cross-section of the arm of the leveling tool. Fig. 3 is a vertical cross-section of the mechanism for actuating the tool. Fig. 4 is a vertical elevation of the tool showing the leveling arm drawn up, or retracted. Fig. 5 is a cross-section of the actuating mechanism on the line 5—5 of Fig. 6 looking in the direction of the arrows. Fig. 6 is a vertical section of the actuating mechanism on the line 6—6 of Fig. 5 looking in the direction of the arrows. Fig. 7 is a horizontal section through the leveling

arms, and Fig. 8 a vertical section through the arms, and mechanism, when the former are drawn up in the position shown in Fig. 4. Fig. 9 is an elevation of a detail on a large scale of the mechanism shown in Fig. 3 for controlling the shafts. Fig. 10 is a plan view of the same mechanism, a portion of which is taken on line 9—9 of Fig. 3, looking in the direction of the arrows.

Similar letters refer to similar parts throughout the several views.

In the drawings, and preferably in Fig. 1, O represents the oven, which is provided with a central opening or eye O¹, in the top and a door D at one side on the level with the floor.

S represents one of a pair of rails, extending along the top of a row of coke ovens upon which moves a carriage, carrying the leveling device, similar to that described and claimed by me in an application for Letters Patent to another form of coke leveling machine, filed by me contemporaneously with this application, in the United States Patent Office under Serial Number 442,305 for coal leveling machines for beehive ovens, now forming the subject of United States Letters Patent No. 1,067,197, of July 8th, 1913. The carriage 1 carries a truck which in turn carries a rotating table 13 actuated as described in said application which in turn carries two beams 14, mounted on trunnions 15 so that they may be adjusted angularly, at any angle to the plane of the table. At one end of the beam 14 is the tower frame 17, which supports and carries the cylinder 18, and the leveling tool proper. The cylinder is raised and lowered by a sprocket wheel as shown in said Letters Patent, which, through the sprocket 21 and worm 22, gives motion to the drum 23, which in turn winds and unwinds the cable 24 carrying the cylinder 18.

In the present form of apparatus, as in that referred to in the aforesaid Letters Patent, the mechanism for inserting and rotating the leveling arms, consists, as appears from Figs. 1, 2, 3, and 4, of a vertical cylinder 18 which is arranged to slide vertically in a cylinder 42. The cylinder 18 fits closely within the cylinder 42 so as to slide vertically therein, and it is provided with a spline, or other connection, which will prevent it from rotating independently thereof, and will cause it to rotate with the cylinder.

der 42 when the latter is rotated. This cylinder 42 is held in a suitable head or bearing 57 on the ends of the arms 14 as shown in Figs. 1 and 3, and it is surrounded at 5 the top by a toothed rack 28, which is splined or bolted to it and which engages with a gear wheel 27 arranged upon suitable bearings in the arm 14 through which a rotary motion may be imparted to the cylinder 10 42 and the cylinder 18, by means of a pulley and belt 26 on the shaft of the gear wheel 27.

In the interior of the cylinder 18, there is 15 a sliding tube 34 which is of such relative dimensions that it fits closely into, and is rotated with the cylinders 18 and 42. The tube 34 carries at its lower extremity a cross-head 68 as shown in Figs. 1 and 2, and to this crosshead is attached a second cylindrical 20 tube 78 which is of larger diameter than tube 34 and fits and can slide over the lower extremity of the latter as shown in Fig. 2. The cylinder 18 is exteriorly flanged at the 25 top as shown in Fig. 3 and is closed at the top by the circular flanged head 81 which is of the form shown, and at the bottom by the circular head 80, the heads 80 and 81 being held together by the vertical rods 82. The head 81 is of the form shown in Fig. 3, and 30 is surrounded by a plate 51 which is permanently attached to it so that as the cylinder 18, and the heads 80 and 81 rise or fall the plate 51 necessarily moves vertically with them. The heads 80 and 81 are driven 35 tightly into the head 18 so as to be practically integral therewith so far as rotation is concerned. The tube 34 passes up into a suitable seat in the head 81 and passes out and through a suitable opening in the head 40 80. A second tube 65 is provided within the tube 34 which passes upward through an appropriate opening in the center of the head 81 as shown in Fig. 3. The exterior of the tube 65 is provided at the lower end 45 with a screw threaded surface as shown in Figs. 3 and 6. The lower extremity of the tube 65 is surrounded by a nut or collar 76 which, as shown in Figs. 2, 5 and 6, is pivoted to the end of the cylinder 78 by the 50 pins 77. The collar 76 is provided on its inner surface with a screw thread corresponding to the screw threaded surface on the cylinder 65, so that by turning the cylinder 65 the nut or collar 76 works up and 55 down and carries with it the tube 78. Slots 69 of appropriate length are provided opposite each other at either side of the cylinder 34 in which the pins 77 are arranged to travel up and down.

60 The leveling arms of which there are two ordinarily, are composed of two tubular portions 31 and 32 and are shown in Figs. 1, 2, 7 and 8. The portions 31 are pivoted by means of the horizontal pivot 10 as shown 65 in Figs. 2, 7 and 8, to the extension 75

which forms the lower end of the tube 78. The pivoted portions 31 are each connected by means of a bracing strut or link 66 as shown in Figs. 1 and 2, with the head 67 on the vertically moving tube 78, and by raising and lowering the tube 78 upon the tube 34, the arms 31 will be raised and lowered by means of the links 66. The outer tubular portion 32 is arranged to slide freely within the inner portion 31 as shown in Fig. 2, and it is moved in the latter by means of a screw rod 33 which passes through a threaded opening in the collar 35. By rotating the rod 33, the part 32 may be moved in and out. The inner end 33 passes through the collar 35 on the inner end of the part 31, and terminates in the beveled gear wheels 74 which engage with the double gear wheels 73, on the horizontal pivot 10. As will be seen from Fig. 4, when the links 66 are in a vertical position, they are off center, so that any downward pressure upon the crosshead 68 has the effect of making the links press downwardly and outwardly on the arms 31, thereby tending to spread them and cause them to fall.

In the interior of the tube 65 is a shaft 64 which extends the entire length of the mechanism. The shaft 64 at its lower end passes out through a bearing in the head 75 on the lower end of the tube 34 as shown in Fig. 8 and carries a beveled gear wheel 72 engaging with the inner faces of the beveled gear wheels 73, the outer faces of which engage with the gear wheels 74. The shaft 64 carries at its upper end a friction wheel as shown in Figs. 7 and 10, which is controlled by a friction band 11 through a lever 12. By moving the lever 12 the friction band 11 surrounding the wheel 62 is tightened or released as described later. The tube 65 is also provided at its upper end with a friction wheel 63, controlled through the lever 14 by a friction band 13. These levers encircle a shaft 60, which is capable of rotation in either direction. The lower end of the shaft 60 rests in a suitable bearing on the upper surface of the platform 57, and the levers 12 and 14 and the plate 51 are so arranged upon the shaft 60 that they slide vertically up and down on the same when the mechanism is raised from or lowered into the coke oven. The shaft 60 carries a hand lever 60^a terminating in a handle 92 as shown in Figs. 9 and 10, and by moving the same from right to left the shaft is rotated a certain distance, actuating the levers 12 and 14. If the levers 12 and 14 are moved in the direction shown by the arrow in Fig. 10, the two arms of the levers 94 and 94^a, travel very nearly at right-angles to and maintain practically constant distances between the pins 91 and 91^a and the points where the brake bands 11 and 13 come in contact with the surface of the wheels 62 and 63. The movement of the 130

5 arm 94 shown in Fig. 10 is away from the points of contact of the bands with the surface of the wheels 62 and 63, and therefore the distance between the pin 91 on Fig. 10 and the point of contact is lengthened and the brake bands 11 and 13 grip the friction wheels, and hold the mechanism at rest. By reversing the movement of the hand lever of arm 60^a the brake bands are released. 10 When a rotary motion is imparted to the shaft 34 the wheels 62 and 63 will rotate with it, but when the tube 65 is held stationary with the revolving tube 34, the collar 76 by reason of the existence of the screw 15 threaded surface on the cylinder 65 will move downward, carrying with it the cylinder 78, and thereupon the links 66, which being pivoted in the head 67 on cylinder 78 will cause arms 31 to assume the horizontal position shown in Figs. 1 and 2. Simultaneously the shaft 64 is held stationary and thereupon the arms 33 are caused to move outward by means of the cog wheel mechanism shown in Figs. 7 and 8 and to cause the 20 outer portions 32 to assume the extended positions shown in Figs. 1 and 2.

The tube 34, and with it the tube 78, are raised and lowered in the platform 57, by means of the chain 24 attached to the yoke 30 51 which passes over pulleys on the top of the tower 17 and is connected with a drum 23 upon which it winds.

The method of operation is as follows: 35 When the apparatus is in use, the arms are drawn up in the position shown in Fig. 4, and the tube 78 is drawn up on the platform 57 so that the cross head 68 and the pin 77 are at the upper end of the slot 69 as shown in Fig. 4. The carriage is then run along 40 on the track to the point where the lower end 75 of the tube 78 comes directly opposite the opening O¹ in the coke oven. The entire mechanism is then lowered by releasing the drum 23. When the brake bands 11 and 45 13 are loose, the wheels 62 and 63 will, owing to the friction between each other and that between 63 and the sleeve 81, rotate with the leveling shaft or tube 34. If, however, the brake bands 11 and 13 are tightened, as 50 heretofore described, the friction wheels 62 and 63 will be prevented from rotating with the tube 34, thus causing a relative motion between the wheels 62 and 63 and the shaft 34, in the one case closing, and in the other 55 case opening the arms 31 with their inner tubes 32, according to the direction of the rotation. The arms 31 cannot be extended beyond a certain maximum position, nor can they be retracted after they close up upon 60 each other. In either case, if the arms are in their innermost position, the rotation of the shaft in one direction and the application of the brakes will have no effect on the arms, as they will be already closed and the 65 wheels 62 and 63 will therefore rotate with

the shaft. If now, the motion of the shaft 34 is reversed, the application of the brakes to the wheels 62 and 63 will cause the arms 31 to be opened and expanded. If the arms 31 are at their outermost position, the rotation of the shaft in one direction and the application of the brakes will have no effect on their position, and therefore none upon the wheels 62 and 63; but by reversing the movement of 34 the brakes will be allowed to operate, thus preventing the wheels from rotating and allowing the arms to be closed. While the arms 31 are being lowered to the horizontal position shown in Figs. 1 and 2, as is accomplished by the action of the brake 13 on the wheel 63, they are extended by means of the action of the brake 11 on the wheel 62 which causes the shaft 64 to remain stationary with reference to the shaft by means of which the horizontal shafts 33 are turned and the arms 32 extended by means of the movement of the collar 35 on the screw threaded surface of the shaft 33. 70 75 80 85

I claim as my invention:

1. In a traveling coal leveling machine 90 for use with beehive ovens, the combination of a vertical member arranged to be lowered from the carriage through the eye of an oven; a leveling arm connected therewith composed of extensible parts and means actuated by the driving mechanism and controlled manually for extending the parts of the arm so as to make it of any desired length, after introduction into the coke oven.

2. In a traveling coal leveling machine 100 for use with beehive ovens, the combination of a vertical member arranged to be lowered from the carriage through the eye of an oven; a leveling arm connected therewith composed of extensible parts and means actuated by the driving mechanism and controlled manually for extending the parts of the arm so as to make it of any desired 105 length, after introduction into the coke oven, and for retracting them to their original position after the leveling has been completed.

3. In a traveling coal leveling machine 115 for use with beehive ovens, the combination of a vertical member arranged to be lowered from the carriage through the eye of a coke oven; means for lowering said member into the oven; an arm connected with the vertical member composed of extensible parts, means for dropping the arm to a horizontal position, means for extending the parts of the arm while being lowered so as to make it of any desired length; and means for rotating parts of the vertical member in different directions as may be desired, substantially as described.

4. In a traveling coal leveling machine 120 for use with bee hive ovens, the combination of a suitable shaft arranged to be lowered from a carriage through the eye of a coke 130

oven, means for lowering the shaft into the coke oven, an arm connected with the shaft arranged to be lowered, composed of extensible parts, means for dropping the arm to a 5 horizontal position, means for extending the parts of the arm while being so lowered, so as to make it of any required length, means for rotating the extended arm in the furnace, means for retracting the parts of the 10 arm, and means for folding them up and lifting the shaft and arms out of the oven when the leveling operation is completed.

5. In a traveling coal leveling machine for use with bee hive ovens, the combination 15 of a vertical member arranged to be lowered from the carriage through the eye of a coke oven; means for lowering said member into the oven; an arm connected with the vertical member composed of extensible telescopic 20 parts, means for dropping the arm to a horizontal position and means for extending the telescopic parts of the arm while being lowered so as to make it of any desired length, and means for rotating parts of the vertical 25 member substantially as described.

6. In a traveling coal leveling machine for use with bee hive ovens, the combination of a suitable shaft arranged to be lowered from a carriage through the eye of a coke 30 oven, means for lowering the shaft into the coke oven, an arm connected with the shaft arranged to be lowered, composed of extensible telescopic parts, means for dropping the arm to a horizontal position, means for 35 extending the parts of the arm while being so lowered, so as to extend the telescopic parts of the arm to any required length, means for rotating the extended arm in the furnace, means for retracting the telescopic 40 parts of the arm, and means for folding them up and lifting the shaft and arms out of the oven when the leveling operation is completed.

7. In a traveling coal leveling machine 45 for use with beehive ovens, the combination of a vertical hollow shaft arranged to be lowered from the carriage through the eye of an oven; two arms connected with the shaft, arranged to be lowered therewith; a 50 cylinder sliding on the shaft, connected with the arms, whereby when the cylinder is lowered the arms are pushed out to a horizontal position; and means within the cylinder for extending and retracting the arms to any required distance, and means for rotating the shaft substantially as described.

8. In a traveling coal leveling machine for use with beehive ovens, the combination of a vertical hollow shaft arranged to be 55 lowered from the carriage through the eye of an oven; two arms connected with the

shaft, arranged to be lowered therewith; a cylinder sliding on the shaft, connected with the arms, whereby when the cylinder is lowered the arms are pushed out to a horizontal 65 position; a rod within the cylinder, engaging by gear mechanism with rods within the arms, for extending and retracting the arms to any required distance, and means for rotating the shaft substantially as described. 70

9. In a coal leveling machine for use with beehive ovens, the combination of a vertical shaft composed of two cylinders placed one within the other, the outer of which is arranged to rotate in suitable bearings on a 75 movable carriage, the whole being arranged to be raised and lowered through the eye of an oven; a central cylinder within the inner cylinder and rotating with the same to which two arms are pivotally connected; a 80 cylinder sliding on the lower end of the central cylinder, whereby when the same is lowered, the arms are pushed out to a horizontal position; a shaft within the central cylinder, engaging with devices which extend or retract the arms to any required distance; devices for holding the central shaft stationary and rotating the other parts of the mechanism in the inner cylinder independently of each other, and means for 85 rotating the entire mechanism in the oven substantially as described.

10. In a coal leveling machine for use with beehive ovens, the combination of a vertical shaft composed of two cylinders placed 90 one within the other, the outer of which is arranged to rotate in suitable bearings on a movable carriage, the whole being arranged to be raised and lowered through the eye of an oven; a central cylinder within the inner 100 cylinder to which two arms are pivotally connected; a cylinder sliding on the lower end of the central cylinder, whereby when the same is lowered, the arms are pushed out to a horizontal position; a shaft within the 105 central cylinder, engaging with gear wheels which actuate rods which extend or retract the arms to any required distance; devices for holding the central shaft stationary and rotating the other parts of the mechanism 110 and the inner cylinder independently of each other, and means for rotating the entire mechanism in the oven substantially as described.

In testimony, that I claim the foregoing 115 as my invention, I have signed my name in presence of two witnesses, this 30 day of June 1908.

WILLIAM SANGSTER.
